UNITED STATES PATENT OFFICE

2,443,014

BEAMING APPARATUS

Thomas F. Suggs, Gastonia, N. C., assignor to
Cocker Machine and Foundry Company, Gas-
tonia, N. C., a corporation of North Carolina

Application November 13, 1946, Serial No. 709,639

14 Claims. (Cl. 28—32)

1

This invention has general reference to beaming apparatus such as used in the textile arts and, more particularly, relates to the species thereof commonly known as beam warpers; the primary object being to provide a novel form of manually-controlled and similarly-operated doffing means whereby the beam, when full of yarn, is easily lowered to floor-level for removal, and correspondingly raised when replaced by an empty beam.

Another object of this invention is to provide a doffing-means of the form above indicated including refinements, whereby the beam is adjustably mounted and accurately positioned in the beam warper with positive assurance of maintaining its correct position during the warping operation.

A further object is to provide a novel means whereby the beam is detachably journaled intermediate the spaced ends of a rotative and a non-rotative shaft means with positive assurance that all of such parts are held in direct coaxial alignment.

A still further object of this invention is to provide a doffing-means of the type above mentioned including means whereby the beam is securely restrained against vertical or other displacement when in active warping position, or when lowered to doffing location.

With the above stated fundamental objects in view and others with ancillary advantages which will be later on referred to or become apparent, to those skilled in the art, upon an understanding of the construction, combination and arrangement of means hereinafter disclosed; but it will also be appreciated said means are susceptible of modification or change from the specific embodiment, typically illustrated by the accompanying drawings, and more particularly defined in the concluding claim.

In the drawings:

Fig. 1 is a front elevation of a tricot beam-warper embodying the improvements of this invention.

Fig. 2 is a side elevation of the same as viewed looking from the right toward the left-hand of Fig. 1.

Fig. 3 is a plan section taken approximately as indicated by the angled-arrows III—III in Fig. 1, with other parts broken out and also in section for a clearer understanding of important details.

Fig. 4 is a vertical section through one of the spaced side columns, hereinafter fully explained, with the beam and associated driving-shaft in the lower, or "doffing," position; and,

2

Fig. 5, is a similar vertical section, to the preceding, but showing the beam and driving-shaft elevated, or in the active warping location.

In describing the form of this invention exemplified by the drawings herewith, specific terms will be employed for the sake of clarity, but it is to be understood the scope of said invention is not thereby limited; each such term being intended to embrace all reasonable equivalents which perform the same function for an analogous purpose.

Referring more in detail to the drawings, the reference character 6 comprehensively designates a "tricot" beam-warper embodying the improvements of this invention; said warper including a reed 7, through which the warps of yarns—not indicated—are drawn from the tensioning means 8 for passage over the cross-over roll 9, and down from the latter to the beam 10 upon which they are collected and wound, in accordance with known practice. The tricot beam-warper 6 comprises spaced columns 11, preferably, although not essentially, of substantially channel formation, and one of which embodies, or has attached thereto, a rearwardly-projecting housing 12 near the lower part thereof, for a purpose later on explained, while it is to be particularly observed that the forward or frontal edges of the column side walls 13 are appropriately enlarged at 14 and shaped to define outwardly-directed bevel-edged lateral flanges 15, which afford directly vertical guidance for individually associated driving head right-and-left hand assembly-carriers or slides 16, 17 respectively. Each slide 16, 17 is provided with inner and outer runners or guides 18, 19 conveniently, although not essentially, attached thereto by suitable securing means 20; whereas rectangularly-stepped parts 21 of the outer guides 19 are fitted with triangular-section inserts 22 for sliding coaction with the bevel-edged flanges 15, above referred to, and such inserts are arranged to be rigidly clamped against the flanges 15 by aid of hand-screws 23 in an obvious manner and for a purpose later on hereinafter explained; it being understood that the inserts 22 are restrained against lengthwise displacement by fillet abutments 24 in the guides 19, see Fig. 2, to best advantage. Preferably the respective spaced columns 11 are braced at their front open portions 50 by appropriate upper and lower cross-webs 25, 26, respectively.

Referring now first to the right-hand slide 16, for example only, which carries or supports a driving-head for the improved beaming apparatus 6, such slide being preferably of rectangular

contour, as best appreciated from Fig. 1, with a correspondingly shaped aperture 27 therethrough; while said slide 16 affords support for a drop-bracket or hanger 28, of channel formation, at its rear as well as spaced bearings 29 at the front thereof. These bearings 29 are conveniently attached in the desired position by securing means 30 and jointly afford rotary support for a drive-shaft 31 and, to the inner end whereof is applied as by key means 32, a movable driving-chuck 33. This driving-chuck 33 is under control of a manually-operable shifter 34, see Fig. 1, which is fulcrumed at 35 to a suitable bracket 36, attached to or forming a part of the slide 16, whereas said chuck is preferably of the cupped type; that is to say it includes a hollow section 37 provided with interior teeth 38 for cooperative engagement with a corresponding gear 39 made fast to the confronting end of the beam spindle 40, in an obvious manner.

The beam-spindle 40 is preferably tubular for reception, at its end remote from the gear 39, of the reduced end 41 of the non-rotative tailstock-shaft 42, which is suitably supported in special bearings 43, 44 conveniently made fast to the slide 17 of the left-hand column 11 by attaching means 45, for instance. Particular attention is directed, at this juncture to the fact that the shaft 42 is enlarged or shouldered at 46 adjoining the reduced end 41, for a reason later on herein explained. It is also to be noted that the bearing 43 embodies vertically spaced lugs 47 between which are fulcrumed, by a pivot element 48, a hand-lever 49 having a fragmentary gear portion 50, at its inner end, for meshing engagement with a toothed rack or key 51, inset in the tailstock-shaft 42, whereby the latter is restrained against rotation but is capable of predetermined longitudinal movement in either direction as later on again referred to; stops 52, 53 on the spaced lugs 47 restrict such movements by coaction with a projection 54, see Fig. 1, on the hand-lever 49.

Turning now to the bearing 44, the same somewhat conforms to the bearing 43, just above described, in that it is of similar size and general contour while being secured to the tailstock-slide 17, by like attaching means 45. On the other hand the bearing 44 is provided with a hollow projection 55 in which is fulcrumed, by a pivot element 56, a hand-lever 57 embodying a cam-portion 58 eccentrically related to said pivot element and whereby the tailstock-shaft 42 is locked in the active position, again referred to herein, while 59 indicates a movement limiting stop for a purpose later on explained.

A suitable housing or cover 60 for the rectangular aperture 27 in the carrier-slide 16, intermediate the spaced bearings 29, is conveniently attached to the carrier-slide 16 by screw-studs 61.

Surmounting and rigidly-connecting the columns 11 is an appropriate frame member 62 affording rigid support not only for the bearings 63, of the cross-over roll 9, but also gear-housings 64 through which are journaled a transverse doffing-control shaft 65; such shaft having keyed to each end thereof a hand-wheel 66, whereby said shaft 65 may be rotated in either direction, as hereafter further amplified. Also keyed on the shaft 65 within the respective housings 64 is a sprocket-gear 67; and on a stub-shaft 68 secured across each said housing 64 is a spacedly related and vertically-adjustable idler sprocket gear 69; while over both of the associated gears 67, 69 there is trained a chain 70 having one end attached medially to the respectively associated

tailstock and head-stock assembly carrier slides 17, 16, whereas the other ends of such chains afford connection for an associated counter-balance weight 71. The outer flight of the respective chains 70 is directed vertically downwards from the idler sprocket-gear 69; whereas the inner flight of each said chain 70 passes similarly through an associated central aperture 72 to its connected counterbalance weight 70, which is located within the respective columns 11, as readily understandable by those conversant with the related arts.

Referring now to the means whereby the sectional or other beam 10 is rotatable to collect or wind the yarn or yarns—not indicated—thereon, the same preferably comprises a multi-groove drive-pulley 73 keyed at 74—Fig. 3—on the drive-shaft 31, a pair of spaced similarly-grooved idler-pulleys 75, 76 on stub-shafts 77 across the hanger 20 of the right-hand column 11, for example; as well as an upper correspondingly-grooved vertically-adjustable idler-pulley or sheave 78 on a transverse shaft 79 across said column, and a similar lower driver-pulley 80 on a transverse counter-shaft 81, also in such column. These pulleys 73, 75, 76, 78 and 80 preferably have trained thereabout endless V-belts 82; the sinuous course of which may be briefly as follows: outwardly and downward about the drive-pulley 73 carried by the bearings 29 then upwardly and over the idler-pulley 76, from which it goes down under the lower driver-pulley 80 on the counter-shaft 81 across the column 11, thence up and over the vertically-adjustable idler-pulley or sheave 78 on the shaft 79; and from the latter down to and partially about the idler-pulley 75 to the first mentioned driver-pulley 73, as clearly understandable from the associated arrows in Fig. 5, whereby the beam 10 is rotated to wind-up yarn or yarns thereon.

Power is appropriately, although not essentially, imparted to the transverse lower counter-shaft 81 through the medium of multi-groove pulley 83 fast on said shaft, with associated V-belt 84 also trained about a correspondingly grooved driver 85 secured on the power-shaft 86 of an electric motor 87; said driver 85 and V-belt 84 being enclosed by the housing or guard 12 at the lower back portion of the column 11, which is provided with an opening 88 for free passage of such belting, in an obvious manner. 89, Fig. 1, indicates a conventional presser roll for coaction with beam 10, and 90 in said figure designates positioning guide rails for entry by the beam end flanges 91 to facilitate insertion and removal of the beam 10, in the warper 6, as hereinafter set forth.

Before proceeding to explain the functioning of the various instrumentalities and structural devices described, it is to be noted that the warper 6 is operative regardless of the elevation of the beam 10, by simply starting the motor 87, and vice versa. Assuming now, that the beam 10 be in the active position of Fig. 5, with the hand-screws 23 tightened-up it will be readily understood that when the motor 87 is activated said beam can be rotated, through the belt drives 82 and 84, until it has collected the desired amount of yarn thereon ready for "doffing" whereupon said motor is stopped. The operator now simply releases or retracts the hand-screws 23 and turns the most convenient hand-wheel 66 counter-clockwise, whereby the associated sprockets 67 are correspondingly rotated under conjoint and uniform movement of the chains 70 with descent

of the respective headstock and tailstock carrier-slides 16, 17, and the opposing pull of the counter-balancing weights 71, whereby the loaded beam 10 is easily and smoothly lowered until its end flanges 91 seat in the guide-rails 90, at floor-level. The operator now swings the hand-lever 57 from the position shown in Fig. 3, until it engages the limit-stop 53 with resultant release of the cam portion 58, from locking or jam-coaction with the tailstock-shaft 42; whereupon the hand-lever 49 is similarly swung until the projection 54 thereof abuts the limit-stop 53 with resultant movement outwards of the tailstock-shaft 42 under coaction of the toothed parts 50, 51, in an obvious manner, to thereby release the shaft-reduced end 41 from engagement in the bore of the beam-spindle 40. The operator now swings the shifter 34 on its fulcrum 35 to move the driving-chuck 33 from meshing coaction of the parts 37, 38, whereby the beam 10 becomes fully released from the warper 6, and can be readily removed in accordance with known practice for replacement by an empty one. In placing an empty beam 10 in the warper 6, see Figs. 3 and 4 more particularly, the procedure just explained is reversed, that is to say said empty beam is initially placed with its flanges 91 in the guide rails 90 whereby it is centralized with respect to the common axis of the head and tailstock shafts 31 and 42; whereupon the driving-chuck is moved into the full-line position of Fig. 1, for intermeshing of the parts 38, 39; it being readily understood that the beam 10 can be easily "jogged" around in the guide rails 90 in the event said parts 38, 39 be slightly out of alignment for sliding interengagement. The operator next moves the hand-lever 49 from contact with the stop 53 into abutment with the stop 52 with incidental progression of the tailstock-shaft 42 inwards and entry of its reduced end 41 into the bore of the beam-spindle 40 with abutment of the enlargement 46 against the outer face of the confronting flange 56; whereupon the hand-lever 57 is swung to the full-line position of Fig. 3 with incidental cam-locking of the shaft 42 against movement in either direction, as aforesaid. The operator now turns either of the hand-wheels 66 in the proper direction to re-elevate the head and tailstock carrier-slides 16, 17 by aid of the chains 70, to the position of Fig. 5, for example, ready for collecting or being filled with yarn when the motor 87 is re-started, as will be well understood by those conversant with the art.

From the foregoing disclosure the merits and efficiency of the apparatus disclosed hereinbefore will be clearly understood but it is desired in conclusion to stress certain features of prime importance. Firstly by turning either of the hand-wheels 66 in the proper direction the operator causes the associated sprocket wheels 67 to correspondingly turn and thereby permit the headstock and tailstock carrier-slides 16, 17, that are attached to the chains 70, to be lowered or raised in unison, while the hand-screws 23 securely clamp said slides elevated in position for the active or beaming operation, as well as when lowered for the purpose of "doffing." Furthermore by seating the housings 64 for the sprockets 67, 69 on top of the hollow columns 11, and since the sprockets 67 are keyed on the doffing control-shaft 65, the carrier-slides 16, 17, with the associated parts, will always be kept in perfect alignment both when said slides are moved up or down.

Finally, while there has been disclosed one practical embodiment of this invention, it is to be understood that changes and variations will be apparent to those skilled in the art in adapting my novel doffing mechanism to differing types and forms of beaming apparatus; and all such changes and variations are hereby contemplated as may be fairly includable within the terms and scope of the following claims.

10 Having thus described my invention, I claim:

1. Doffing means for beaming apparatus comprising spaced supports; counterbalanced carriers for rotatively sustaining a beam, guided directly vertical by said supports, and movable to place the beam in yarn receiving position; means for moving the beam into doffing location and for returning the carriers to the position aforesaid, after mounting an empty beam thereon; and means for restraining said carriers against displacement when in active warping position or when located for doffing the beam.

2. Doffing means for beaming apparatus comprising spaced columns; counterbalanced carrier heads for rotatively sustaining a beam, guided directly vertical by said columns to place the beam in yarn receiving position; manually operable means for simultaneously lowering the beam carrier heads into doffing location, and for re-elevating the same to the position aforesaid after placing an empty beam therebetween; and means for securing the carrier heads against displacement in the active warping position or when lowered for doffing the beam.

3. Doffing means for beaming apparatus comprising spaced hollow columns; counterbalanced headstock and tailstock assemblages guided directly vertical by and slideable along said columns; axially aligned means, sustained by the respective headstock and tailstock assemblages, for the intervening rotative-support of a beam in yarn receiving position; manually operable means for concurrently lowering the assemblages aforesaid with placement of the beam in doffing location, and for re-elevating such assemblages after insertion of an empty beam therebetween; and means for securing the respective assemblages in either warping position or doffing location.

4. Doffing means for beaming apparatus comprising spaced hollow columns; counterbalanced headstock and tailstock assemblages guided directly vertical by and slideable along said columns; axially aligned means sustained by the respective headstock and tailstock assemblages for the intervening rotative-support of a beam in yarn receiving position; manually operable means for concurrently lowering the assemblages aforesaid with placement of the beam in doffing location, and for re-elevating such assemblages after insertion of an empty beam therebetween; means for rigidly clamping the individual assemblages in either warping position or doffing location; and means whereby one of the assemblages is operated to concurrently rotate the beam when in warping position.

5. Doffing means for beaming apparatus comprising spaced and vertically-slotted hollow columns; counterbalanced head-and-tailstock assemblages guided by and movable along the slots in said columns; axially aligned rotative and non-rotative shafts individually sustained by the respective assemblages for the intervening removable support of a beam in yarn-receiving position; manually actuatable mechanism for concurrently lowering the tailstock assemblages for placement of the beam in doffing location, and for

re-elevating such assemblages after insertion of an empty beam concentrically aligned between the rotative and non-rotative shafts; individual means manually operative to effect securement of the respective assemblages against displacement in either warping position or when in doffing location; means operatively coordinating the headstock assemblage with a source of power to effect rotation of the beam when in warping position; and means for axially centralizing an empty beam alignedly between the rotative and non-rotative shafts for coupler-connection to the former and relatively revolvable support by the latter.

6. The invention of claim 5 wherein the respective columns are of approximately channel formation with the free edges enlarged and shaped to define bevel-edged lateral flanges; and wherein one of said columns embodies an outwardly-projecting housing, for the respective purposes specified.

7. The invention of claim 5 wherein the headstock assemblage comprises a carrier element having vertical side portions suitably shaped for slidable coaction with the column slot edges; wherein laterally spaced bearings on said element afford rotative support for a drive-shaft; wherein in a clutch-chuck is slidably mounted on the inner end of said shaft; and wherein a shifter is fulcrumed to the carrier element with provisions for coaction with the chuck to move the latter into and out of active engagement with the confronting end of the beam spindle, for the purpose specified.

8. The invention of claim 5 wherein the tailstock assemblages comprise a carrier element slidably engageable with the associated column vertical-slot side edges; wherein laterally spaced bearings on said element afford non-rotative support for a shaft; wherein one of said spaced bearings includes a pivotal hand-lever having a gear portion at its inner end; wherein a toothed key, inset into the shaft aforesaid, is in mesh with the hand-lever geared end; and wherein means limit movement of said hand-lever to effect reciprocation of the shaft in either direction, for the purposes specified.

9. The invention of claim 5 wherein the tailstock assemblage comprises a carrier element slidably engageable with the associated column vertical slot side edges; wherein laterally spaced bearings on said element afford non-rotative support for a shaft; wherein one of said spaced bearings includes a pivotal hand-lever having a gear portion at its inner end; wherein a toothed key inset into the shaft aforesaid is in mesh with the hand-lever geared end; wherein means limit movement of said hand-lever in either direction; wherein the other of the spaced bearings includes a pivotal hand-lever embodying an eccentrically related cam portion lockingly coactive with the non-rotative shaft; and wherein stop means limit movement of the last mentioned hand-lever in one direction, for the purpose specified.

10. The invention of claim 5 wherein the head-and-tailstock assemblage counterbalancing

means comprise individually connected suspension chains trained over spaced sprockets at the top of the respective hollow columns; wherein the relatively inner flight portions of said chains are within the columns and have counterweights attached to the free ends thereof; wherein a common operating shaft is keyed through an aligned pair of spaced sprockets; and wherein hand wheels are fixed to the respective ends of said shaft, for the purpose specified.

11. The invention of claim 5 wherein the means effective to secure the head-and-tailstock assemblages against displacement in the warping position or doffing location comprise a grooved guide element in each said assemblage; wherein a triangular section bar is inset in said guide element; and wherein screw means engage said bar to force the latter into jamming engagement with the confronting side wall edge of the associated column.

12. The invention of claim 5 wherein the means operatively coordinating the headstock assemblage with a source of power to rotate the beam comprise a multi-grooved pulley fast on the drive-shaft portion of said beam; wherein a multiplicity of similar idler and a driver pulley are journaled within the headstock associated column; wherein endless V-belts are trained about the pulleys aforesaid; and wherein the last mentioned or driver-pulley is correspondingly and directly coordinated to the power shaft of a suitable motor.

13. The invention of claim 5 wherein the means for axially centralizing an empty beam between the rotative and non-rotative head-and-tailstock shafts consist of suitable guide rail stops perpendicularly below the axis of rotation of said beam when in warping position.

14. The invention of claim 5 wherein the beam spindle is of tubular form with a gear section at one end for clutch engagement by the headstock rotative shaft; and wherein the other end of said spindle receives the reduced confronting end portion of the tailstock non-rotative shaft.

THOMAS F. SUGGS.
